Filed Mar. 19, 1957, Ser. No. 647,151

10 Claims. (Cl. 84—236)

The invention relates to a musical instrument, and more in particular to a musical instrument comprising a plurality of resonators each adapted to be actuated by striking one of the keys of a key board. Examples of instruments of this kind are the piano, the harpsichord, and the clavichord.

In the known instruments of this kind, a rather complicated transmission mechanism is provided between each key and the actuating member striking the associated resonator. This makes the construction of these instruments very expensive.

It is an object of the invention to simplify this transmission mechanism.

Another object of the invention is to provide musical instruments of the above-mentioned kind which are fully equivalent to the known instruments and have the same touch, but of which the costs are considerably lower.

Still another object of the invention is to provide relatively inexpensive toy- and study-instruments of the above-mentioned kind.

A further object of the invention is to provide a musical instrument of the above-mentioned kind of which the timbre may be changed in a relatively easy manner, for instance from a piano timbre into a harpsichord timbre, or vice versa.

A still further object of the invention is to provide a suitable combination of springs and magnets for transmitting the movement of the keys to the actuating members striking the resonators in musical instruments of the above-mentioned kind.

According to a main feature of the present invention, the movement of the keys is transmitted to the associated actuating members by means of springs which are temporarily held by means of magnets, so as to obtain a suitable snap or trigger action.

The resonators of the instrument according to the invention may be of any desired kind. In general, strings will be used, but use may also be made of metal tubes, bells or other resonators. It is generally preferable to use elongated resonators horizontally arranged with their longitudinal axes in parallel with the keys.

The exact nature of my invention, and any additional objects thereof will appear from the following description of a preferred embodiment, given with reference to the accompanying drawings.

In the drawings:

Fig. 1 is partially a side view, and partially a longitudinal section of a key with its associated transmission mechanism.

Fig. 2 is a perspective view of the instrument as a whole.

Fig. 3 shows a detail of the transmission mechanism.

In Fig. 1, a key 1 is pivotably supported by a pin 3 mounted in a beam 2; at its end, the key is guided by a pin 4. To the left of the point of rotation of the key, a spring blade 5 is attached to the underside of the key body; at its free end, this spring blade carries an armature 6. Near its middle, the spring blade is

2

supported by a block 7, so that the armature 6 is spaced at some distance from a permanent magnet 8, fixedly arranged under the armature. Preferably, the part of the spring blade between its connection with the key body and the supporting block 7 is made more rigid than the remaining part, for instance by placing a second spring blade 22 against spring blade 5 throughout the first-mentioned part of the latter.

When the key is struck, the left end of the key body moves in upward direction, whereby the spring blade 5 is lifted from its support 7. This causes the spring blade to bend, so that the armature 6 is laid on the permanent magnet 8 and is held thereby for the time being. Upon further movement of the key, the tension of the spring blade increases continually, until the force of attraction between the armature and the magnet is overcome and the spring blade is suddenly released. The hammer rod 9 supported by the upper side of the armature 6 is now suddenly moved in upward direction, 20 so that the hammer head 10 attached to the top of the rod 9 impinges on the string 11 arranged above the key. During this movement, the hammer rod is guided by a grid beam 12 fixedly arranged in the instrument.

At the same time as the rod 9, a rod 13 carrying a damping member 14 is moved in upward direction. The rod 13 is guided by a grid beam 15. When the key is released, the rod 13 falls back with its abutment 20 on a comb-shaped member 21. The member 21 may be adjusted with the aid of a pedal in two positions, so that the damping member 14 either falls on the string 11 or not, as desired. In the first case, the tone is damped immediately after release of the key, in the second case the tone continues.

The armature 6 is preferably made of a strip of soft iron, folded around the end of the spring blade 5 and clamped to this blade. A metal block serving as a support for the hammer rod 9 is attached to the said strip.

Setting screws 16, 17 and 18 are provided in the key body in order that the tension of the spring blade may be adjusted in such manner that the desired operation is obtained. At the spots where the spring blade contacts other parts during its movement, felt cushions are provided either on the blade or on the said other parts. For instance, a felt cushion 23 is provided on the upper surface of the permanent magnet 8, a felt cushion 23a is provided on the block supporting the hammer rod 9, and a felt cushion 24 is provided on the upper surface of the spring blade at the setting screws 16 and 17.

As appears from Fig. 2, the instrument has substantially the shape of a grand piano. The horizontal strings 11 are in parallel with the keys. The pedal 19 serves for adjusting the comb-shaped member 21 (Fig. 1). The manner in which the comb-shaped member 21 may be displaced by the pedal 19 is well-known in the art, so that a detailed description would appear to be superfluous. It is pointed out, however, that the pedal 19 is pivoted in the middle, so that a depression of the lower part (at the left in Fig. 2) causes the rod 25 to be lifted, whereby the comb-shaped member 21 is lifted at the same time.

Fig. 3 shows a detail of the transmission mechanism in the position taken during the initial part of the movement of the key. As appears from the drawing, the armature 6 consists of a relatively long strip of soft iron, of which one end has been folded around the end of the spring blade 5 and clamped to this blade, while the other end of the strip has not been attached to the spring blade. Thus, this latter end lies against the setting screw 17 during the initial movement of the key. This construction has the advantage that the armature 6 does not impinge on the magnet 8 with a considerable force, so that interfering noises are avoided. To the right of

the supporting block 7, the spring blade consists of two superposed blades, as mentioned hereinbefore.

Although my invention has been described hereinbefore with reference to a specific embodiment, it is to be understood that various alterations and modifications may be applied thereto within the scope of the invention as set forth in the appended claims.

I claim:

1. A musical instrument, comprising a plurality of pivotable keys arranged to form a key board, a plurality of horizontally arranged resonators each associated with one of the said keys and each having its axis in parallel with the associated key, a plurality of vertical, axially displaceable hammer rods each associated with one of the said keys and placed underneath the associated resonator, a plurality of hammer heads each attached to the upper end of one of the said hammer rods and adapted to strike the associated resonator upon axial displacement of the associated hammer rod, a plurality of spring blades each connected with one of the said keys for movement thereby and having its free end below the under end of the associated hammer rod to displace said hammer rod and actuate said resonator upon movement by said key, a plurality of ferromagnetic elements each carried by one of the said spring blades, and a second plurality of ferromagnetic elements fixedly arranged in said instrument and each underneath one of the elements of said first-mentioned plurality of ferromagnetic elements, the elements of at least one of the said pluralities of ferromagnetic elements being permanently magnetized, whereby, when a key is struck, the associated spring blade is first held by the mutual attraction of the associated ferromagnetic elements, but is suddenly released upon further movement of the key when the said attraction is overcome by the spring tension, so that the associated hammer rod is thrust upwards and the associated resonator is struck.

2. A musical instrument, comprising a plurality of pivotable keys arranged to form a key board, a plurality of resonators each associated with one of the said keys, a plurality of spring blades each attached to the underside of one of the said keys on the side of its pivot remote from said key board, a plurality of armatures each carried by the free end of one of the said spring blades, a plurality of permanent magnets fixedly arranged in said instrument and each opposite to one of the said armatures so as to hold the same when in contact therewith until the mutual attraction is overcome by the tension of the associated spring blade, a plurality of hammer rods each associated with one of the said keys and having one of its ends opposite to the free end of the associated spring blade so as to be displaced thereby when said spring blade is released by the associated permanent magnet, a plurality of hammer heads each attached to the other end of one of the said hammer rods and adapted to actuate one of the said resonators upon displacement of the associated hammer rod, and a plurality of supporting members each supporting one of the said spring blades near the middle thereof, whereby the associated armature is spaced from the associated permanent magnet in the position of rest of the associated key, and whereby, when a key is struck, the associated spring blade is first lifted from its supporting member, so that it is caused to bend and to contact the associated permanent magnet with its armature.

3. A musical instrument as claimed in claim 2, wherein the part of each of the said spring blades between its

connection with the associated key and the associated supporting member is more rigid than the remaining part of said spring blade.

4. A musical instrument, as claimed in claim 2, wherein the part of each of the said spring blades between its connection with the associated key and the associated supporting member is composed of two superposed blades.
5. A musical instrument as claimed in claim 2, wherein the said resonators are horizontally arranged each with its axis in parallel with the associated key.
6. A musical instrument as claimed in claim 2, wherein the said hammer heads are detachable from the said hammer rods.
- 15 7. A musical instrument as claimed in claim 2, further comprising a plurality of setting screws mounted in the bodies of the said keys for adjusting the said spring blades, wherein each of the said armatures comprises a relatively long strip of soft iron of which one of the ends 20 has been folded about the free end of the associated spring blade and clamped to the latter, while the other end of said strip is movable with respect to the associated spring blade and lies against one of the said setting screws during the initial movement of the associated key.
- 25 8. A musical instrument as claimed in claim 2, wherein cushions of felt are provided at the spots where each of the said spring blades contacts other parts during its movement.
9. A musical instrument as claimed in claim 2, further 30 comprising a plurality of damping members each associated with one of the said keys and adapted to be displaced in upward direction when the associated key is struck, an abutment for the said damping members on which they fall back after release of the associated key, 35 and a pedal for adjusting said abutment so that the said damping members may either fall on the associated resonators or not, as desired.
10. In a musical instrument the combination which 40 comprises actuating means comprising a movable key, a pair of mutually magnetically attracting elements, one of said elements being an armature element and the other of said elements being a holding element, means resiliently connecting said armature element to said actuating means to resiliently urge the armature element along a path of movement when said key is moved, a 45 resonator mounted at a location spaced from said armature element, hammer means mounted for movement into and out of acting contact with said resonator, said hammer means being positioned in the path of movement of said armature element to be mechanically moved thereby into acting contact with said resonator, said holding element being mounted to hold said armature element at one end of said path of movement opposite to said hammer means against the resilient urging of said 50 connecting means when said key is moved until sufficient energy is stored in the connecting means upon continued movement of said key to overcome the magnetic attraction of said elements and catapult said armature element along said path of movement into said hammer means 55 thereby causing said hammer means to strike said resonator.
